MISSILE

Michael M. Kamimoto, China Lake, Calif., assignor to the United States of America as represented by the Secretary of the Navy

Filed June 30, 1952, Ser. No. 296,508

3 Claims. (Cl. 102—50)

(Granted under Title 35, U.S. Code (1952), sec. 266)

The invention described herein may be manufactured and used by or for the Government of the United States of America for governmental purposes without the payment of any royalties thereon or therefor.

This invention relates in general to missiles, and more particularly to improvements in flight controls for rockets.

One of the objects of the invention is to provide an improved system for controlling the azimuthal and elevational directions of movement of a missile, and controlling roll thereof about its axis of movement.

Another object is to actuate the directional control surfaces of the missile by the ambient fluid through which the missile moves.

Another object is to actuate the control surfaces of a rocket by ram pressure produced by movement of the missile through air.

Another object is to provide a differential fluid pressure operated diaphragm device for actuating a control surface.

Another object is to provide a plurality of pairs of differential pressure operated diaphragm devices for actuating azimuthal and elevational control surfaces, and a gyroscope for controlling said surfaces to effect roll correction of the missile.

Other objects and many of the attendant advantages of this invention will be readily appreciated as the same becomes better understood by reference to the following detailed description when considered in connection with the accompanying drawings wherein:

Fig. 1 is a fragmentary side elevation of a rocket to which the subject of the invention is applied;

Fig. 2 is a section taken on line 2—2, Fig. 1, internal details being omitted;

Fig. 3 is a section taken on line 3—3, Fig. 4, and an enlarged section taken on line 3—3, Fig. 2, portions being broken away;

Fig. 4 is a section taken on line 4—4, Fig. 3;

Fig. 5 is a section taken on line 5—5, Fig. 3;

Figs. 6 and 6A are sections taken on line 6—6, Fig. 3;

Fig. 7 is an enlarged section taken on line 7—7, Fig. 1, a portion being broken away;

Fig. 8 is a section taken on line 8—8, Fig. 7;

Fig. 9 diagrammatically illustrates the control system;

Fig. 10 is a section taken on line 11—11, Fig. 11, portions being broken away;

Fig. 11 is a section taken on line 11—11, Fig. 10;

Fig. 11A is a section taken on line 11A—11A, Fig. 11, showing another position of parts;

Fig. 12 is a section taken on line 12—12, Fig. 10; and

Fig. 13 is a section through a conduit and valve of Fig. 9;

Referring in detail to the drawing, and particularly Figs. 1 to 8, rocket 20, movable along its longitudinal axis A, is of any conventional form, which embodies the subject of the invention. The rocket casing or tube 21 is provided with four air scoops 22, 22a, 22b, 22c, spaced equiangularly about its periphery. Fixed fins 23,

2

23a, 23b, 23c are carried by the rocket rearwardly of the respective scoops and each carries a movable fin. Since the fin scoops and fin actuators are all identical the description of one will serve for all. As best shown in

5 Figs. 4 to 8, a sheet of flexible material 19 is clampingly held between the side plates of fixed fin 23 and between the side plates of movable fin 24, this serving to permit swinging movement of fin 24 about axis 25, as best shown by the dotted positions, Fig. 5. A pair of elongated hollow flexible diaphragms or bags 26, 27 are secured to the inner wall of tube 21 by a plate 28 and a pin 29 affixed thereto, pin 29 having a flange 30 engaging the bottom wall of a recess 31 and adapted to rock in a transverse plane of the rocket, as best shown in Figs. 6 and 6A. The outer end 32 of the pin is convex and seats within a socket 33 carried by the inner edge of fin 24. In Fig. 6, bags 26, 27 have the same internal ram pressure and fin 24 is in the solid line position shown in Fig. 5, that is, in alignment with the direction of flight of the rocket.

10 In Fig. 6A, a differential pressure exists in bags 26, 27, bag 26 being larger in cross section than bag 27, which has tilted plate 28 and its attached pin 29, swinging fin 24 to one of the dotted positions of Fig. 5. It will be apparent that when bag 27 expands and bag 26 contracts, fin 24 will be moved to the other dotted line position of Fig. 5. The actual amount of angular movement will depend on the differential pressure in the two bags. The front ends of both bags communicate with air scoop 22, and the rear ends are both closed, as best shown in Figs.

15 30 7 and 8. A pipe 34 communicates with the rear end of bag 27 and a similar pipe 35 communicates with the rear end of bag 26. As diagrammatically shown in Fig. 9, similar bags 26a, 27a actuate fin 24a; bags 26b, 27b actuate fin 24b; and bags 26c, 27c actuate fin 24c.

20 35 As best shown in Figs. 9 and 13, pipes 34, 35b are connected to a normally closed solenoid operated valve V₁, which, when opened, will bleed air from pipes 34, 35b through vent port P₁. Pipes 35, 34b are similarly connected to valve V₂ and port P₂. Pipes 34a, 35c are similarly connected to valve V₃ and port P₃, and pipes 35a, 34c are similarly connected to valve V₄ and port P₄.

25 Assuming that the system is provided with only the construction so far described, the operation is as follows:

40 45 When valve V₁ is open and valve V₂ closed, air will bleed out through port P₁, reducing the pressure in pipes 34, 35b thus effecting a differential pressure between bags 26, 27 and 26b, 27b, respectively, thus swinging fins 24, 24b in the same direction. As will be apparent, if valve V₂ is open and valve V₁ closed, these fins will be swung

50 55 in the opposite direction. Similarly, when one of valves V₃, V₄ is open and the other closed, fins 24a, 24c will swing in one direction or the other, depending upon which of these valves is open. The solenoids may be controlled by any suitable intelligence which dictates change of direction and signals a corrective control to the valves. As will be apparent, one pair of opposite fins controls azimuthal direction of flight and the other pair controls elevational direction of flight.

60 65 Roll of the rocket about its axis or direction of flight is also controlled by the fins just described by moving opposite pairs thereof in opposite directions. A rotor 37, of a gyroscope, 38, provided with buckets 39, is mounted for rotation by shaft 40 in gimbal 41, the latter being rotatable about axis 42 on pintles 43 rotatably supported by the rocket. A pipe L₁ communicates with pipe 34 and terminates in frame 44, delivering air to jet 45. Pipe L₂ communicates with pipe 35 and terminates in frame 44, delivering air to jet 46. Before the gimbal has precessed, the ends of pipes L₁, L₂ are misaligned from the air receiving ends of jets 45, 46, respectively, by the same amount, as best shown in Fig. 12, so that there is equal flow of air to both jets. When the gimbal precesses, one

70

of the jets becomes more nearly aligned with its supply pipe and the other less aligned with its supply pipe, thus changing the relative rates of flow through lines L₁ and L₂. Pipe L₃ communicates with pipe 35b, and pipe L₄ communicates with pipe 34b, these pipes similarly terminating in frame 44 and supplying air to jets 47, 48, respectively, which latter are misaligned with pipes L₃, L₄ in the same manner described for jets 45, 46. Assuming that valves V₁ and V₂ are closed and the gyroscope precesses as shown in Fig. 11A, pipe L₁ will become less aligned with jet 45, and pipe L₂ will become more nearly aligned with jet 46, and the pressure in pipe L₁ will be greater than in pipe L₂. Due to the similar misalignment of pipes L₃, L₄ with jets 47, 48, respectively, the pressure in pipe L₄ will be greater than in pipe L₃. Bags 27 and 26b will then collapse and bags 26 and 27b expand, thus moving fins 24, 24b in opposite directions. As will be apparent, if the gyroscope precesses in the opposite direction, the opposite movement of fins 24, 24b will be opposite to that just described. The opposite direction of movement of opposite pairs of fins will, as will be apparent, apply a corrective force opposing roll of the rocket. The other pair of fins 24a, 24c are similarly controlled by the gyroscope through pipe L₅, terminating in frame 44 above pipe L₄, and pipe L₆, terminating above pipe L₃, at one side of the gimbal, and pipes L₇ and L₈ terminating, respectively below pipes L₂, L₁, at the other side of the gimbal. It will be apparent, therefore, that when a roll correction is required, fins 24 and 24b will move in opposite directions and fins 24a and 24c will also move in opposite directions, the roll correction of the pairs being cumulative.

Assuming again that the pressure in pipes L₁, L₄ are greater, respectively, than in pipes L₂, L₃ (which would effect a roll correction) and valve V₁ is now opened, the pressure differential between pipes L₄ and L₃ will then become greater and the pressure differential between pipes L₁ and L₂ will become less. Fins 24, 24b, instead of being swung in opposite directions in equal angular amounts will now move so that fin 24b is swung a greater amount, and fin 24 a lesser amount, thus retaining substantially the same roll correction as formerly, but now producing an azimuthal steering correction. As will be apparent, opening of valve V₂ instead of valve V₁ produces an opposite effect. Opening of valve V₁ (or V₂) does not affect the position to which fins 24a, 24c have been previously moved by the gyroscope control and the net roll correction thus remains substantial as it formerly was with an azimuthal steering correction added to the roll correction. Similarly, if valve V₃ or V₄ is opened while the fins are moved to a roll correction position, the net roll correction remains substantially as it formerly was with an elevational correction added to the roll correction.

Obviously many modifications and variations of the present invention are possible in the light of the above teachings. It is therefore to be understood that within the scope of the appended claims the invention may be practiced otherwise than as specifically described.

What is claimed is:

1. Directional flight control and roll control apparatus for a missile comprising; first and second vertical fins movably carried by the missile at substantially diametrically opposite sides thereof adapted to control azimuthal direction of movement of the missile, third and fourth horizontal fins movably carried by the missile at substantially diametrically opposite sides thereof adapted to control elevational direction of movement of the missile, a first pair of flexible expandable chambers operatively connected to the first fin adapted to move same in opposite directions from a normally neutral position in response to gas pressure applied within said chambers, second, third, and fourth pairs of similar chambers similarly connected, respectively, to said second, third and fourth fins adapted to similarly move same, means for applying the same gas pressure to all of said chambers when said fins are all in their neutral positions, first valve means for reducing the pressure in one chamber of the first pair and one chamber of the second pair to effect differential pressure between the respective pairs and effect movement of the first and second fins in one direction, second valve means for reducing the pressure in the other chamber of the first pair and the other chamber of the second pair to effect differential pressures in the respective pairs and effect movement of the first and second fins in the opposite direction, whereby said first and second valves control the azimuthal direction of flight, third and fourth valves similarly connecting the third and fourth pairs of chambers for controlling the elevational direction of movement, a gyroscope carried by the missile, and valve means operable in response to precession of the gyroscope for reducing the pressure in said one chamber of the first pair of chambers and said other chamber of the second pair, or reducing pressure in said other chamber of the first pair and said one chamber of said second pair, whereby said first and second fins move in opposite directions and correct roll of the missile about its direction of movement, said last named valve means being adapted to similarly control said third and fourth fins for also correcting roll.
2. Apparatus in accordance with claim 1 including means for delivering ambient air under ram pressure to all of said chambers to apply said gas pressure therewithin.
3. Apparatus in accordance with claim 2 wherein said valve means is constructed and arranged to deliver air from at least some of said chambers to said gyroscope for rotating its rotor.
